UNITED STATES PATENT OFFICE

2,523,815

PICTURE FRAME

Harold S. Cloyd, Erie, Pa., assignor to National Organ Supply Company, Erie, Pa., a corporation of Pennsylvania

Application January 22, 1945, Serial No. 573,848

3 Claims. (Cl. 40—156)

1

In picture frames of cast or molded material there is a tendency of the material to cold flow or warp, causing the frame to draw away from the glass, particularly at the corners. These effects are accentuated if the back fastening produces points of stress concentration. This invention is designed to overcome these difficulties and to provide an improved back fastening particularly applicable to cast or molded frame constructions. Further objects and advantages appear in the specification and claims.

In the accompanying drawing, Fig. 1 is a back view of the picture frame; Fig. 2 is a back view with some of the back fastenings omitted; Fig. 3 is an enlarged view of one of the back fastenings; Fig. 4 is a plan view of one of the corner pieces; and Fig. 5 is a section on line 5—5 of Fig. 3.

Referring to the drawing, there is shown a rectangular picture frame having sides 1 and ends 2 sloping rearwardly toward the outer edges. On the rear face of the frame is a ledge 3 for receiving a glass 4, a picture 5 and a back 6 which may be provided with a stand 7. At the outer periphery of the ledge 3 are side and end rails 8 and 9 projecting from the rear face of the frame beyond the back. The glass is held against the ledge by corner pieces 10 and 11 at the lower and upper corners of the frame. The corner pieces are provided with tongues 12 receivable in slots 13 at the junctions of the side and end rails and tongues 14 receivable in slots 15 in the side and end rails. The upper corner pieces 11 can be molded integral with the frame or have the tongues cemented in place and the inner edges 16 are bevelled on the under side so the picture, glass and back can be slid into place. The lower corner pieces 10 are removable and are provided with ridges 17. In order that the glass may be held tightly against the ledge, slots 13 and 15 can be provided with a slight outward slope toward the front of the frame.

The frame is adapted to casting from thermo-plastic material with the rails integral with the sides and ends of the frame. The slots 13 and 15 may be molded in the rails. The corner pieces 10 and 11 may be made of the same material. While thermo-plastic material is obtainable in a wide variety of colors, it is subject to warping and is also subject to cold flow. It is therefore desirable that localized stress in the back fastening be avoided and that the frame be held tightly against the glass which stiffens the frame and prevents warping. This is obtained in the present construction by locating the fastening means at the corners since the corners of the frame

2

have a tendency to warp away from the glass and by providing relatively wide tongues on the corner pieces which distribute the holding stress along the rails.

5 While the slots may be molded integral with the rails of the frame, it is also possible to mold the rails or slot forming pieces separately and cement them in place, thereby obtaining an integral construction identical with the molded 10 construction.

It may also be desirable to locate retaining pieces 18 at intermediate points along the rails. These retaining pieces are provided with tongues 19 receivable in slots formed in the rails. The 15 retaining pieces may also be provided with buttresses 20 which engage the inside of the rail.

What I claim as new is:

1. A frame for pictures or the like having a ledge on its rear face for receiving a glass and 20 back, side and end rails bounding the ledge and extending rearwardly from the frame, slots in adjacent side and end rails and at the corner therebetween, and a triangular corner piece adapted to rest against the back and having edges 25 engaging the side and end rails at one side of the slots, and tongues projecting from said edges through said slots, said tongues and slots, when the corner piece is rested on the back in the position to slide along the back into the corner, 30 being aligned in the direction of movement of the corner piece.

2. A frame for pictures or the like having a ledge on its rear face for receiving a glass and back, side and end rails bounding the ledge and 35 extending rearwardly from the frame, adjacent rails being joined at a corner, slots in the rails on each side of the corner, a retainer extending across the corner having the intermediate portions resting against the back and edges engaging

40 the rails at one side of the slots, and tongues projecting from said edges through the slots, said tongues and slots, when the retainer is rested on the back in position to slide along the back into the corner, being aligned in the direction of 45 movement of the retainer.

3. A cast frame for pictures and the like adapted to thermo-plastic material, comprising an integral rectangular frame having sides and ends sloping rearwardly toward the outer edges, 50 a ledge on the rear face of the frame for receiving a glass and back, stiffening rails bounding the ledge extending rearwardly from the frame and joined at the corners, slots in the rails at the corners, and triangular corner pieces adapted 55 to rest against the back and holding the glass

against the ledge, said corner pieces having edges engaging the rails at one side of the slots and tongues projecting from said edges through the slots, and said tongues and slots, when the corner pieces are rested on the back in position to slide along the back into the corner, being aligned in the direction of movement of the corner piece.

HAROLD S. CLOYD.
